UNITED STATES PATENT OFFICE

121,371

DESIGN FOR A COMBINED CONTAINER AND SOAP DISPLAY

Ethel M. Hammond, New York, N. Y.

Application November 28, 1939, Serial No. 88,519

Term of patent 7 years

To all whom it may concern:

Be it known that I, Ethel M. Hammond, a citizen of the United States of America and residing at Borough of Manhattan, city, county, and State of New York, have invented a new, original, and ornamental Design for A Combined Container and Soap Display, of which the following is a specification, reference being had to the accompanying drawing, forming part thereof.

In the drawing:

Fig. 1 is a perspective view of a combined container and soap display showing my new design; and

Fig. 2 is a top plan view thereof.

I claim:

The ornamental design for a combined container and soap display, as shown.

ETHEL M. HAMMOND.
